CLAIM

The ornamental design for a sandpaper tool, as shown and described.

DESCRIPTION

FIG. 1 is a perspective view of a sandpaper tool.

FIG. 2 is a front elevational view thereof.

FIG. 3 is a rear elevational view thereof.

FIG. 4 is a top plan view thereof, the bottom plan view being a mirror image of the top plan view; and,

FIG. 5 is a left side elevational view of the sandpaper tool, the right side elevational view being a mirror image of the left side view.
